UNITED STATES PATENT OFFICE.

ARTHUR L. CURREY, OF CHICAGO, ILLINOIS.

BOTTLE-STOPPER.

1,233,757.

Specification of Letters Patent.

Patented July 17, 1917.

Application filed July 7, 1916. Serial No. 107,926.

To all whom it may concern:

Be it known that I, ARTHUR L. CURREY, a citizen of the United States, residing at Chicago, in the county of Cook and State 5 of Illinois, have invented a certain new and useful Improvement in Bottle-Stoppers, (Case 1,) of which the following is a full, clear, concise, and exact description, reference being had to the accompanying drawings, forming a part of this specification.

My invention relates to bottle stoppers and broadly stated, the object of my invention is to produce a stopper of cork or other suitable material provided with means 15 whereby the stopper may readily and easily be withdrawn from its associated bottle or other receptacle without using a cork screw or other extraneous stopper removing device.

As will more fully hereinafter appear, I provide a device desirably in the form of an integral piece of sheet metal, which is arranged to be inserted into the stopper conveniently at the time the latter is made, the 25 device being conformed to lock itself into the body of the stopper when so inserted, and thus to all intents and purposes constituting an integral part of the stopper. The device referred to comprises a head conveniently provided with an eye and a shank integral with the head and projecting therefrom, with that 30 end of the shank opposite the head pointed to facilitate the insertion of the shank into a stopper. At a number of points along a 35 number of points along its lateral edges the shank is cut or slit along lines oblique to the edges of the shank, and the metal adjacent said slits is turned outwardly from the plane of the shank to provide pointed wings which serve securely to 40 lock the shank in the body of the stopper when the shank is inserted into the stopper. The head is desirably so arranged that it may be turned from the plane of the shank to the plane of the stopper top, so that the 45 head is out of the way when not in use.

In the accompanying drawings,

Figure 1 is a view in perspective of a bottle provided with a stopper embodying the improvements of my invention;

Fig. 2 is an axial sectional view of a stopper illustrating the shank of the stopper removing device in side elevation;

Fig. 3 is an edge view in elevation of the stopper removing device;

Fig. 4 is an elevational view of a modified

form of stopper removing device, partially completed;

Fig. 5 is an edge view in elevation of the device shown in Fig. 4 in completed form, the stopper being illustrated in dotted lines, 60 and

Fig. 6 illustrates a stopper provided with a slightly modified stopper removing device.

In Fig. 1 at 10 I have illustrated a bottle provided with a stopper 11 of any suitable 65 material, but preferably cork. At 12 is illustrated the stopper removing device which characterizes my present invention. This stopper removing device preferably consists of a single piece of sheet metal 70 conformed to provide a shank 13 and a head 14, the head 14 being provided with an aperture 15. That end of the shank opposite the head 14 is desirably pointed in order that the stopper removing device may be inserted into the 75 stopper, as is most clearly illustrated in Fig. 2. At a plurality of points along its lateral edges the shank 13 is slit along lines oblique to the lateral edges of the shank, and the metal adjacent said slits is turned from the 80 plane of the shank to provide a plurality of upwardly pointing sharpened ears 16—16. It will be noted that certain of the ears 16—16 project from one side of the shank 85 and the other ears from the opposite side of the shank. In providing a stopper with the removing device the sharpened end of the shank is thrust downwardly into the body of the stopper preferably until only the head 14 projects from the stopper, as is illustrated in Fig. 2. It will be understood that the upwardly pointing ears 16 permit the shank to be thus inserted into the stopper, but effectually serve to engage in the stopper to prevent the withdrawal of the shank. I 95 find it desirable to construct the stopper removing device of metal sufficiently tough and pliable to permit the head 14 to be turned at right angles to the shank, and so that it lies parallel to and immediately adjacent the upper surface of the stopper, as is 100 illustrated in Fig. 1. The stopper removing device is thus normally out of the way. When the stopper is to be removed the head 14 is raised to lie in the plane of the shank, 105 as shown in Fig. 2, and the head 14 may be grasped to remove the cork. In cases where the stopper fits rather tightly a nail, pencil or other similar article may be inserted through the aperture 15, and the very good 110

hold thus afforded renders the removal of the stopper a very simple matter.

It will be seen that after the stopper removing device has been inserted into the 5 associated stopper the stopper and stopper removing device constitute an inseparable unit.

The stopper removing device illustrated in Figs. 4 and 5 is provided with a relatively 10 long and narrow shank having three oblique slits therein, two at one edge of the shank and one at the opposite edge. Where a long narrow shank is desired three very effective sharpened ears or prongs may be provided 15 by slitting the shank as illustrated in Figs. 4 and 5.

While I prefer that the head of the stopper removing device shall lie within the 20 margins of the stopper top when the head is turned to lie parallel to the stopper top a head of larger size may be employed, as 25 shown in Fig. 6. When the arrangement shown in Fig. 6 is made use of the aperture in the head may be sufficiently large to permit a finger to be inserted therein.

Attention is called to the fact that the lower end of the shank terminates above the 30 bottom of the stopper and that therefore the metal of the stopper removing device cannot affect or be affected by the contents of the bottle.

Having thus described my invention, what I claim as new and desire to secure by Letters Patent of the United States is:

35 1. An extractor comprising an integral flat metal shank pointed at one end, whereby it may be inserted in a stopper of cork or the like, said shank having a plurality of slits formed therein along lines extending 40 downwardly and angularly from its lateral edges, the metal adjacent said slits being turned from the plane of the shank to provide upwardly pointing projections substantially as set forth.

45 2. In combination with a stopper, an extractor comprising a flat metal shank embedded in the stopper and projecting downwardly from the top thereof, and a pointed ear on the shank provided by forming a slit 50 in one of the edges of the shank and turning the metal adjacent said slit from the plane of the shank.

55 3. A device adapted to be inserted in a bottle stopper for the purpose set forth comprising an integral piece of flat metal conformed to provide a shank pointed at one

end and having an apertured head at its other end, the said shank being slit from its edges along lines oblique thereto and the metal adjacent said edges being turned from 60 the plane of the shank to provide pointed projections which prevent the shank from being withdrawn after it is inserted in a stopper.

4. A device adapted to be inserted in a 65 stopper for the purpose set forth, comprising an integral piece of flat metal conformed to provide a shank pointed at one end, said shank being slit from its lateral edges along lines oblique thereto, and the metal 70 adjacent said slits being turned from the plane of the shank to provide pointed ears which prevent withdrawal of the shank after the latter has been inserted in a stopper.

75 5. A device arranged to be inserted in a stopper for the purpose set forth, comprising a flat metal shank slit from its edges along lines oblique thereto and having the metal adjacent said slits turned from the 80 plane of the shank to provide pointed projections which prevent withdrawal of the shank when the latter is inserted in a stopper.

85 6. In combination with a stopper a metal member comprising a shank embedded in the stopper and projecting from the top thereof, an aperture in the projecting end of said metal member and pointed ears on said shank formed by slitting the shank 90 from its lateral edges along lines oblique thereto and turning the metal adjacent said slits from the plane of the shank.

95 7. In combination with a stopper, an extractor comprising an apertured head and a 100 straight flat metal shank formed integral with said head, said shank extending into the upper surface of the stopper and embedded in the stopper, and a plurality of pointed projections in said shank provided by forming slits in the shank, each slit extending from one edge of the shank toward the middle thereof, and turning the metal adjacent said slits from the plane of the shank.

105 In witness whereof, I hereunto subscribe my name this 10th day of June, A. D. 1916.

ARTHUR L. CURREY.
